ATTORNEY.

UNITED STATES PATENT OFFICE.

RICHARD DE PLANQUE, OF PHILADELPHIA, PENNSYLVANIA.

PLAQUE FOR PAINTING AND DECORATION.

SPECIFICATION forming part of Letters Patent No. 231,657, dated August 31, 1880.

Application filed April 16, 1880. (No model.)

To all whom it may concern:

Be it known that I, RICHARD DE PLANQUE, a subject of Prussia, (having declared my intention of becoming a citizen of the United States,) have invented a new and useful Improvement in Plaques or Shapes for Painting and Decoration, which improvement is fully set forth in the following specification and accompanying drawings, in which—

Figures 1 and 2 are face views of plaques embodying my invention. Fig. 3 is a section in line $\alpha\alpha$, Fig. 1, enlarged.

Similar letters of reference indicate corresponding parts in the several figures.

My invention consists of a plaque formed, essentially, of pasteboard, binders' cloth-boards, or other similar paper material, prepared in such manner as to be light, durable, and cheap, and to possess other advantages, as will be hereinafter fully set forth.

Referring to the drawings, A represents a plaque, which may be circular, oval, or other desired shape for painting, ornamentation, and decoration generally.

In preparing the plaque I take pasteboard, binders' cloth-boards, or other similar paper material, a , and cut the same into proper shape and saturate it with glue-water, after which, while it is wet, it is stamped or pressed into a dishing form, and when dry it will be found to retain its shape, owing to the stiffening action of the glue. The plaque is now coated on both sides with a compound of glue and whiting, as at $b b'$, and applied thick to the side which corresponds with the front or face of the plaque, and said thick coating is sandpapered or otherwise treated or ground in order to have a uniform and smooth sur-

face imparted to it, which surface then receives a finishing coat of turpentine and pigment, oil, paint, or other similar material, and the plaque is ready for sale and use.

If desired the material a may have designs in relief or intaglio stamped on it, so that the finished plaque is similarly ornamented.

It will be found that the article is light and durable, is without blisters, the surface is uniform and serviceable and may be washed, and readily takes and holds the painting, coloring, or other decorations without chipping, peeling, &c., thereafter.

I am aware that plaques have been made of wood, which warps and cracks, and of terra-cotta, which is heavy, friable, and of an absorbent nature, all of which defects are remedied by my construction.

Having thus described my invention and stated the advantages thereof, what I claim as new, and desire to secure by Letters Patent, is—

1. The method or process of manufacturing plaques, consisting in first saturating a sheet or body of paper with glue, then pressing it into the required shape, then coating it with a mixture of whiting and glue, and finally coating it with some pigment, substantially as set forth.

2. A plaque consisting of paper saturated with glue, stamped into the required shape, coated with glue and whiting, and finally coated again with pigment.

RICHARD DE PLANQUE.
